UNITED STATES PATENT OFFICE

163,096

SPIRAL OLIVE RACK

Mario B. Del Conte, Brooklyn, and Edmund L.
Del Conte, Richmond Hill, N. Y.

Application September 7, 1950, Serial No. 12,089

Term of patent 14 years

(Cl. D44—1)

To all whom it may concern:

Be it known that we, Mario B. Del Conte, a citizen of the United States, residing in Brooklyn, Kings County, State of New York, and Edmund L. Del Conte, a citizen of the United States, residing in Richmond Hill, Queens County, State of New York, have invented a new, original, and ornamental Design for a Spiral Olive Rack, of which the following is a specification, reference being had to the accompanying drawing, forming a part hereof.

Fig. 1 is an elevational view of a spiral olive rack embodying our new design.

Fig. 2 is a top plan view thereof.

Fig. 3 is a bottom plan view thereof.

We claim:

The ornamental design for a spiral olive rack, as shown.

MARIO B. DEL CONTE.
EDMUND L. DEL CONTE.
